MOP FOR USE WITH VACUUM CLEANERS

Theo Sydney Hooks, North Brighton, Victoria,
Australia, assignor to Electrolux Corporation,
Dover, Del.

Application April 29, 1933, Serial No. 668,651
In Australia June 13, 1932

2 Claims. (Cl. 15—158)

This invention relates to a mop adapted for attachment to the suction head of a vacuum cleaner to form a marginal fringe of strands around the latter and enable floors or other surfaces to be polished at the same time that they are being cleaned by the vacuum cleaner.

The mop is suitable for attachment over the usual metal suction nozzle of the vacuum cleaner or over the brush attachment usually supplied with the cleaner, and it is so constructed that it can be fitted onto or removed from the suction nozzle or brush attachment both quickly and conveniently, while yet being effectively retained against accidental dislodgement when in use. 15 Another object of the invention is to provide for vacuum cleaners a mop which is capable of being securely fitted onto suction nozzles or brush attachments of various shapes and sizes.

The mop consists basically of a band to encircle the suction head, mop strands carried by said band, and means for detachably retaining the mop in position on the suction head. The retaining means comprises a roll or a thickened portion on the inner surface of the band to engage the suction head. The band or the roll or the thickened portion may have incorporated elastic means which permits the mop to be stretched when fitting it onto the suction head. Additional fastening means such as tying tapes, 30 cross bands or a strap and buckle may also be provided.

In the accompanying drawing to which reference is made:—

Fig. 1 is a perspective view illustrating one form of the mop shown detached from the vacuum cleaner.

Fig. 2 is a sectional view showing the mop fitted onto the brush attachment of a vacuum cleaner.

Fig. 3 is a perspective view of another form of the mop.

The mop comprises a fabric band 1 adapted to fit around the periphery of the brush attachment 2 of the vacuum cleaner or the suction nozzle 3, as the case may be, and having the mop strands 4 sewn to its lower edge. The mop is shaped to fit closely upon the brush attachment or suction nozzle, and for this purpose the band 1 at the end portions 5 of the mop is shaped to 45 substantially pocketed formation, as shown, to receive the end portions of the brush or suction nozzle. The inner surface of the band 1 is provided with a stuffed roll 6 which is adapted to fit below the edge 7 of the brush, or above the 55 lip 8 of the metal suction nozzle when the mop is fitted in position thereon and thus prevent accidental dislodgement of the mop when being used.

In the form of mop illustrated in Figs. 1 and 60 2, a strip 9 of elastic webbing or like elastic

material is incorporated in the mop band 1 to permit longitudinal stretching of the latter when fitting the mop onto the brush 2 or suction nozzle 3. The mop strands 4 are continued across the elastic portion 9 by being sewn to the lower edge of the latter, but the stuffed roll 6 preferably does not extend across said elastic portion. The strip 9 is attached at its ends to the band 1 by sewing and may be of any convenient length.

When the mop is being fitted onto the brush 2 or the suction nozzle 3, the elastic strip 9 permits the fabric band 1 to stretch, thus enabling the mop to be drawn or pulled onto the brush or nozzle without requiring removal of the latter from the suction tube 10 of the vacuum cleaner. The contraction of the elastic strip 9 after the mop has been correctly fitted causes the band 1 to securely grip the surface of the brush or nozzle and thus firmly hold the mop in position. The stretch permitted by the elastic strip 9 also enables the mop to be conveniently fitted onto brushes or suction nozzles of different shapes and sizes.

In the slightly modified form of mop shown in Fig. 3, the elastic strip 9 instead of being of square or rectangular shape as in Fig. 2 is made triangular in shape with its apex portion 11 at the upper edge of the band 1 and the wide or base portion 12 at the lower edge of the band. 90 This shape of elastic strip permits a greater amount of stretch of the band 1 at its lower edge than at the upper edge and will be found to facilitate the fitting of the mop onto the brush or nozzle and to reduce possibility of the mop becoming dislodged while in use.

What I do claim is:—

1. A mop adapted for attachment to the suction head of a vacuum cleaner comprising a band to encircle the suction head, mop strands carried by the band, an elastic insert in said band, said elastic insert also carrying mop strands, the lower inner portion of the band except the elastic insert being thickened and rolled to provide means to engage the suction head of the cleaner and retain the mop in position.

2. A mop according to claim 1, wherein the elastic insert is of triangular formation, the base of the triangle being along the lower edge to give the rolled portion the greater elasticity.

THEO SYDNEY HOOKS.
